UNITED STATES PATENT OFFICE

LAWRENCE C. PECK AND JAMES HENRY LAMBERT, OF ELY, NEVADA

ILLUMINATED ADVERTISING CALENDAR

Application filed January 26, 1932. Serial No. 588,974.

This invention relates to a combined calendar and advertising sign and in accordance with the present invention an illuminated device is provided which serves the purpose of a calendar, and advertising sign, and in general a business directory.

Also, in accordance with the present invention, means is provided for rendering conspicuous on the calendar a particular date, and especially the present date.

The invention together with its many objects and advantages will be best understood from a study of the following description, taken in connection with the accompanying drawings wherein:

Figure 1 is a front elevational view thereof.

Figure 2 is a vertical transverse sectional view therethrough.

Figure 3 is a transverse longitudinal horizontal sectional view therethrough.

Figure 4 is a vertical longitudinal sectional view through the device.

Figure 5 is a fragmentary longitudinal sectional view through an upper portion of the device and particularly a reflector sign mounted thereon.

Figure 6 is a fragmentary plan view with parts broken away and shown in section to illustrate the manner of securing one lower corner of a transparent panel in position opposite the calendar face of the device.

Figure 7 is a perspective view of a travelling electric lamp.

Figure 8 is a perspective view of one of the guides for the lamp shown in Figure 7.

Figure 9 is a plan view of a month card.

Figure 10 is a similar view of a day card.

Figure 11 is a similar view of an indicia bearing card.

With reference more in detail to the drawings it will be seen that the device comprises a substantially rectangular casing 5 having a rear wall 6, vertical end walls 7, and a front wall 8 disposed slightly inwardly from the open front side of the casing.

The wall 8 is in the nature of a skeleton frame structure and is suitably apertured to provide adjacent each end thereof an advertising card accommodating opening 9 elongated vertically; and a third advertising card

accommodating opening 10 extending between the lower end of opening 9 and elongated horizontally.

Adjacent the upper edge thereof between the opening 9, the front wall 8 is provided with a horizontal row of openings including end openings 11 within which are arranged plates 12 preferably of isinglass and having on the outer or exposed face thereof numerals indicative of the particular year. Between 55 the openings 11 is an intermediate opening 13 having arranged therein a month card 14, the same being preferably formed of isinglass and having the name of the month printed, inscribed or otherwise formed on one 60 face thereof.

Below the openings 11, 13, there is arranged a transverse series of openings 15 within which are arranged cards 16 bearing 70 on the faces thereof the name of the day of the week.

The remaining portion of the front wall 8 are horizontal and vertical rows of openings 17 the proper one of which, to the requisite number, accommodates cards or plates 18, 75 these cards 18 being also formed by the glass, whereby to complete the calendar. It will be noted that there is at least one additional horizontal row of such openings 17, and these may be used for accommodating cards having substantially the same shape and formed 80 from the same material as the cards 18 but upon which are suitable data, legend or the like preferably of an informative nature.

Cards 19 having on their faces suitable advertising data preferably may be arranged in vertical rows in the vertical openings 9 and arranged in a horizontal row in the opening 10 as clearly suggested in Figure 1. To the outer side of the wall 8 is disposed a 90 frame 20 secured adjacent its corners, in position at the open side of the casing 5 through the medium of screws or other fastening elements 21. The frame 20 has mounted therein vertical bars 22 spaced inwardly from the ends of the frame a distance corresponding substantially to the width of the vertical opening 9 in wall 8 and serving with the end members of the frame 20 to retain transparent panels 52 to the outer side of the wall 95 100

8 and for substantially closing the openings 9.

The bars 22 are connected by a horizontal bar 23 which serves with the lower or bottom frame member, to retain a transparent panel 24 in a position substantially closing the opening 10 in wall 8.

A transparent panel 25 serves to close the openings 11, 13, 15 and 17 and the lower edge 10 of the transparent panel 25 rests upon the frame member 23. The panel 25 is retained in place adjacent the lower corners thereof through the medium of glazier's points 26 as best shown in Figure 6, and at its upper edge 15 through the medium of a spring clip 27 engaging therewith and mounted on the upper member of the frame 20 as shown in Figure 1.

The casing 5 also includes a bottom wall, together with a top wall, the latter being indicated by the reference numeral 57. Mounted on the top wall 57 is a reflector sign 28 including a casing, the open side of which is aligned with an opening 29 in the top wall 57. The sign 28 also includes the inclined 29 mirror, apertured front wall, transparent panel closing said front wall, and the indicia bearing card 30 which in the present instance is preferably provided with such data pertaining to the intended purpose of 30 this invention, as for example in the present instance the card 30 has the legend "Business directory."

Suitably supported by relatively short rods 31 extending inwardly from the rear wall 6 of 35 the casing is a vertical series of relatively spaced guide bars 32, there being one guide bar 32 for each horizontal row of apertures 17. Each guide bar 32 is provided with a slot 33 elongated longitudinally thereof and opening 40 at one end of the guide bar.

Shiftable longitudinally of a selected guide bar 32 is an arm 34 provided at one end with a retaining head, and provided at its other end with a lamp socket with which is connected 45 an electric bulb 35 serving as a "spot light". Extending from the socket is a bracket arm 36 provided at its free end with a reflector 37. The lamp cord 38 extends through a suitable opening in the rear wall 6 from any suitable 50 source of supply. Pull cords 39 extends in opposite direction from the socket of the lamp 35 and extend outwardly of the casing through suitable openings provided in the end walls 7 as suggested in Figures 3 and 4.

The arm 34 has the headed end thereof 55 engaged with a slot of a selected guide rod 32, and each successive day is advanced longitudinally of the guide bar inwardly from the open end of the slot to a position substantially opposite the card 18 having thereon the numeral 60 indicative of the particular day of the month that is, ninth, tenth day, etc.

It will be apparent, that the arm 34 travels the length of one bar once within the period of 65 a week, or portions of the length of the bar in

accordance with the number of cards 18 in that row of apertures 17 opposite to the guide rod 32 with which the arm 34 is engaged. At the beginning of each successive week the arm 34 is initially engaged with the proper 70 guide rod 32, and it will be apparent that as the lamp 35 moves opposite to the particular card 18 that card will be especially illuminated thus rendering that card 18 especially 75 conspicuous so that one when using the device 75 for determining the particular day of the week and month will be attracted to the card so conspicuously illuminated.

There is also mounted in the casing 5 adjacent each end thereof vertically disposed 80 tubular electric lamps 39 the cords of which are designated by the reference character 40. The electric lamp 39 will not only serve to illuminate the casing generally, or as a whole, but also serves sufficient light to permit of 85 proper operation of the deflector unit 28.

Referring again to certain details of construction, it is to be understood that the top and bottom, rear and end walls of the casing 90 are to be made of a suitable composition, wood, 90 or any other material as found desirable.

From the foregoing it will be seen that we have devised a practical combination calendar and illuminated advertising sign, which may especially be used to advantage in bank lobbies, hotel lobbies, writing rooms and the like, and which may be readily mounted on a wall, the device not only serving in a very practical manner, but being also highly attractive and decorative. 100

Even though we have herein shown and described the preferred embodiments of our inventions, it is to be understood that we do not wish to limit ourselves to the particular details of construction, combination and arrangement of elements as herein shown and described, and in no wise do we intend to limit the invention beyond the requirements of the prior art and scope of the appended claim. 105

Having thus described our invention, what 110 we claim as new is:

In a device of the character described, a member provided with a plurality of horizontal and vertical rows of apertures, transparent cards in the apertures bearing indicia 115 germane to a calendar, a plurality of vertically spaced horizontal guide bars mounted rearwardly of said member parallel to the horizontal rows of apertures, an arm engageable with a selected one of said guide bars, and an electric lamp mounted on said arm. 120

In testimony whereof we affix our signatures.

JAMES HENRY LAMBERT.
LAWRENCE C. PECK.
